(57) **CLAIM**

The ornamental design for a truck system dashboard, as shown and described.

DESCRIPTION

FIG. 1 is an isometric view of the truck system dashboard as viewed from the passenger's side, showing our new design. FIG. 2 is an enlarged isometric view of the map drawer with the drawer retracted.

FIG. 3 is an enlarged isometric view of the map drawer with the drawer extended.

FIG. 4 is an enlarged isometric view of the map drawer with the drawer cover retracted.

FIG. 5 is a front view.

FIG. 6 is a rear view.

FIG. 7 is an enlarged left side view.

FIG. 8 is an enlarged right side view.

FIG. 9 is a top view; and,

FIG. 10 is a bottom view.

The broken line showing of environment is for illustrative purposes only and forms no part of the claimed design.
